UNITED STATES PATENT OFFICE.

RICHARD S. PORRO, OF NEW YORK, N. Y.

DESIGN FOR A BELT-POCKET.

SPECIFICATION forming part of Design No. 23,683, dated October 9, 1894.

Application filed July 27, 1893. Serial No. 481,661. Term of patent 3½ years.

To all whom it may concern:

Be it known that I, RICHARD S. PORRO, of New York city, in the county and State of New York, have invented a new and original 5 Design for a Belt-Pocket, of which the following is a specification, reference being had to the accompanying drawings, forming a part thereof, in which—

Figure 1 represents the pocket in perspective, and shaped in accordance with my design; and Fig. 2 is a plan view of the same.

The leading features of my design consist in the shield like portion B upon which is produced the circular representation A. The 15 shield shape portion B constitutes the front

and the flap like portion, the circular representation A being produced upon the front of the shield shape part B, a depression or incurved representation C being produced at the top of the circle A and the pocket when viewed from above presenting an elongated mouth D, one wall of which is straight and the other curved.

I claim—

The design for a belt pocket, substantially 25 as herein shown and described.

RICHARD S. PORRO.
